STAND FOR HEARTH TOOLS

Willis S. Hobson, Seymour, Ind., assignor to Seymour Manufacturing Company, Seymour, Ind., a corporation of Indiana

Application April 3, 1957, Serial No. 45,566

Term of patent 14 years

(Cl. D33—17)

FIG. 1.

FIG. 2.

FIG. 3.

Fig. 1 is a top plan view of a stand for hearth tools showing my new design;

Fig. 2 is a side elevational view thereof, and

Fig. 3 is a front elevational view thereof.

I claim:

The ornamental design for a stand for hearth tools, substantially as shown.
